UNITED STATES PATENT OFFICE.

AUGUSTUS O. BOURN, OF PROVIDENCE, RHODE ISLAND, ASSIGNOR TO NATIONAL RUBBER COMPANY, OF SAME PLACE.

DESIGN FOR ORNAMENTATION OF RUBBER BOOTS AND SHOES.

Specification forming part of Design No. 5,098, dated July 11, 1871.

To all whom it may concern:

Be it known that I, AUGUSTUS O. BOURN, of the city and county of Providence and State of Rhode Island, have originated a new Design for the Ornamentation of Rubber Boots and Shoes, of which the following is a specification:

My design consists in the peculiar roughening of the exposed rubber surfaces, in whole or in part, as fully represented in the accompanying photographic illustrations, to which reference is made, and in which it will be observed the exterior rubber surfaces resemble that of grained or pebbled leather.

I claim as my invention—

The design described and shown for the ornamentation of rubber boots and shoes.

AUGUSTUS O. BOURN.
